UNITED STATES PATENT OFFICE

JOSEPH GEORGE, OF WILKES-BARRE, PENNSYLVANIA

CHANGEABLE SIGN

Application filed September 29, 1930. Serial No. 485,174.

This invention relates to a changeable sign designed primarily for window display purposes.

One of the objects of the invention is to provide a sign simulating an airship and utilizing a fan which not only has the appearance of the propellor of an airship, but also while in motion, sets up a circulation of air within the show window so as to prevent the formation of frost on the window and render the sign visible at all times to persons outside of the window.

Another object is to provide a sign having movably supported sign holders adapted to be brought successively to view within windows provided therefor.

A still further object is to provide a structure of this character which utilizes an ordinary electric fan the motor of which serves to operate the several working parts.

With the foregoing and other objects in view which will appear as the description proceeds, the invention resides in the combination and arrangement of parts and in the details of constructions hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings—

Figure 1 is a view partly in side elevation and partly in section showing the present improvements.

Figure 2 is a section on line 2—2, Figure 1.

Figure 3 is an enlarged elevation of one of the changeable sign units.

Figure 4 is a section on line 4—4, Figure 3.

Figure 5 is an elevation of another unit of the sign.

Figure 6 is a section on line 6—6, Figure 5.

Figure 7 is a view more or less in diagram showing the sign suspended in a show case and operating to maintain air currents whereby frosting of the window is prevented.

Referring to the figures by characters of reference, 1 designates the casing of the sign which is in the form of a shell shaped to

simulate the body of an airship. This body is provided with spaced windows 2 and 3 and arranged within one end portion of the body is the motor 4 of an ordinary electric fan the blades of which have been indicated at 5. The motor is of that type having speed reduction gearing in a housing 6 whereby a shaft 7 is driven at greatly reduced speed. In many types of fans this shaft, which rotates at slow speed, is used for causing the fan to swing from side to side. In the present instance, however, the motor and other portions of the fan structure are held against swinging and the shaft 7, instead of being utilized for producing a slow lateral swinging of the parts, is provided with a pulley 8.

Erected in the casing 1 are parallel shafts 9 and 10. The shafts are provided with pulleys 11 arranged in pairs and mounted on the pulleys are endless belts 12 and 13. The window 3 is arranged between the shafts 9 and 10 and in front of the belts.

Interposed between the shafts 9 and 10 is an intermediate shaft 14 having a pulley 15 adapted to receive motion through a belt 16 from the pulley 8. Another pulley 17 is secured to shaft 14 and transmits motion through a belt 18 to a pulley 19 on shaft 9.

Suspended from the belt 12 is a series of boxes 20, each of which has one or more spring clips 21 for detachably engaging belt 12 and supporting the boxes.

Arranged in each of the boxes 20 is a display card 22 on which an advertisement can appear, this card being disposed in an inclined position as shown so as to be easily seen and read by a person looking through the window 3. All of the boxes 20 can be located as close together as desired and the clips 21 are so proportioned that they can travel within the grooved peripheries of the pulleys 11.

Arranged in the rear end portion of casing 1 is a longitudinal shaft 23 having a pulley 24 adapted to receive motion through an endless belt 25 from a pulley 26 on the shaft 10. Suitably located guide pulleys 27 can be provided for the belt 25.

Secured to shaft 23 are spaced disks 28 connected by radial blades 29. Pivotally mounted

ed in the angles formed by these blades are panels 30 adapted to swing freely. Each panel carries on the two sides thereof any suitable advertising or other display matter. Each panel is also provided on its two sides with cushioning buttons 31 of rubber or the like.

It is designed to arrange the parts so that during the rotation of shaft 23 the panels 10 30 will be brought forwardly in upstanding positions successively as shown in Figure 4 so as to expose one face of each panel through window 2. After the panel is moved past a dead center it will drop downwardly onto the blade 29 thereunder and ultimately be brought to a hanging position as shown at the bottom of Figure 4, thereby to expose the display matter on the other side of the panel.

The various belts and pulleys constitute 20 speed reduction gearing so that the signs will move slowly and simultaneously.

If desired a supplemental display device 25 or ornament indicated generally at 32 can be arranged above the casing 1 and mounted on shaft 14 so as to rotate therewith.

The entire structure is adapted to be suspended in a show case or window by means 30 of wires 33 or the like and when the electric motor is set in operation the blades 5 will act to set up strong air currents which will prevent the formation of frost on the windows W. Consequently persons looking 35 through the windows can readily see the sign and the changeable display matter carried thereby.

What is claimed is:

1. A changeable sign including a casing, 40 an electric fan in one end portion thereof including a motor, a slow speed shaft, and a fan, there being a window in the casing, mechanism within the casing for bringing different signs successively into position for exposure through the window, and means for transmitting motion to said mechanism from the slow speed shaft.

2. A changeable sign including a casing having a window, mechanism movably mounted in the casing for displaying different signs successively through the window, 50 mechanism carried by the casing for setting up a circulation of air around the casing, and means driven by said mechanism for actuating the sign displaying mechanism positively and at a reduced speed.

3. A changeable sign including a casing, 55 said casing having a window, mechanism in the casing for displaying signs successively through the window, and means carried by the casing for setting up a circulation of air 60 there around and for actuating said mechanism, said means including an electric fan including blades supported outside of the casing, and a slow speed shaft supported within the casing, said shaft being operatively 65 connected to the mechanism.

4. A changeable sign including a casing having a window, parallel endless belts movably mounted within the casing adjacent to the window, holders detachably mounted on and suspended from one of the belts and bearing 70 backwardly against the other belt, an electric fan structure mounted in the casing and having blades located outside of the casing, and a low speed shaft, and means for transmitting motion from the low speed 75 shaft to said belts thereby to successively display the holders through the windows, the blades of the fan constituting means for maintaining a circulation of air outside of the window to prevent formation of frost 80 on a transparent container in which the sign is located.

In testimony that I claim the foregoing as my own, I have hereto affixed my signature.

JOSEPH GEORGE.
